UNITED STATES PATENT OFFICE.

MICHAEL DOWNEY, OF BOSTON, MASSACHUSETTS.

CAR-COUPING.

SPECIFICATION forming part of Letters Patent No. 239,034, dated March 22, 1881.

Application filed January 3, 1881. (No model.)

To all whom it may concern:

Be it known that I, MICHAEL DOWNEY, of Boston, county of Suffolk, State of Massachusetts, have invented a new and useful Improvement in Car-Couplings, of which the following description, in connection with the accompanying drawings, is a specification.

My invention relates to a car-coupling, and has for its object to produce a strong and simple coupling which is automatic in action.

My improved coupling consists, essentially, of a holding-dog pivoted in the draw-head, and having a projection to engage a corresponding notch in the connecting-link, which, when inserted in the draw-head, as the cars come together, engages a shoulder upon the holding-dog, turning it on its pivot to cause its projection to enter the notch of the link, after which a locking device automatically comes into position to retain the said dog engaged with and holding the link securely. When it is desired to unshackle the cars the said locking device is properly moved to allow the holding-dog to turn on its pivot, and the projection thereon and notch in the link being preferably V-shaped, or having their engaging faces inclined to the line of action of the pulling force, the said dog will be turned aside on its pivot as soon as any strain is brought upon the said link to pull it from the draw-head. The locking device is operated to release the holding-dog by a suitable lever or handle adapted to be operated from the top of a car by means of a chain or other suitable connector. The opening in the draw-head is made of considerable width measured vertically, and one end of the link is made to fit with tolerable snugness therein, it being held laterally between one side of the said draw-head and the holding-dog, while the other end of the said link is made of a considerably less depth than the opening in the draw-head, to enable it to enter therein in case the two draw-heads to be connected are not at the same height from the rails.

Figure 1 is a top view of a car-coupling embodying my invention, the upper portion of the draw-heads being broken away to show the interior mechanism; Fig. 2, a side elevation thereof; and Fig. 3, a modification showing a link adapted to connect cars, one of which

has my improved draw-head and the other a draw-head of ordinary construction.

The draw-heads *a a'*, connected by draw-bars to the body of the car in any usual manner, contain the holding-dogs *b b'*, pivoted at 2, and provided with holding-points 3, shown as V-shaped projections, to engage corresponding holding-points 4 at either end of the link *c*. The said dogs have a squared shoulder, 9, 60 adapted to be brought by the link, when entering the draw-head, into coincidence with the squared end of the said link, the dog being rotated on its pivot to accomplish this result, and its holding-point 3 brought into engagement with the holding-point 4 of the link by the same movement. The portion 6 of the link, which is to be last joined to its draw-head, is made narrower vertically than the portion 5, that is secured in its draw-head before the cars are coupled together, it projecting from the middle of the said portion 5, so that in case the draw-heads are not at the same height or do not register properly the said thin portion 6 of the link will enter somewhere in the said opening.

A locking device (shown as a block, *e*, pivoted at 7 on the inner face of the draw-head) is adapted to fall down between the holding end 3 of the dog *b* or *b'* and the side of the draw-head, to prevent the said dog from rotating on its pivot to disengage the holding-points 3 4 of the said dog and link.

A lifting-toe, *i*, on the inner face of the draw-head, below the block *e*, is connected with the squared end of a pivot, *m*, extended out through the side of the draw-head, and connected with a lever, *n*, adapted to be operated by a chain, *o*, to turn the said toe on its pivot, and thereby cause it to engage and raise the block *e*, as shown in dotted lines at the right hand, Fig. 2, bringing the said block opposite a recess, 8, in the dog *b* or *b'*, to allow the holding-point of the said dog to be turned aside to permit the link to be inserted or removed. The movement of the lever *n* is limited in either direction by the stops *s s'*, which allow the lifting-toe *i* to be removed just sufficient distance to properly operate the locking device *e*.

In operation, when desired to couple two cars, the blocks *e* are raised to allow the holding-points of the dogs to be turned aside, as

shown at the right hand, Fig. 1, to permit the link to enter the draw-head, and when thus turned aside the block *e* will rest in the recess of the said dogs, being supported thereby, and 5 the toe *i* will be dropped, as shown at the left hand, Fig. 2. The thick end 5 of the link *e* will then be inserted by the operator in the opening of one of the draw-heads, as the one *a*, Fig. 1, and upon striking the shoulder 9 of 10 the dog *b* therein will turn the said dog in its pivot, bringing the holding-point 3 thereof into engagement with the one 4 of the link *c*, and by the same movement allowing the block *e* to fall down behind the said dog and prevent it 15 from being rotated back on its pivot to disengage the link until the said block is again raised by the operator turning the lever *n*. When the cars come together, after the link *c* has been thus inserted and held in the draw- 20 head *a*, the thin end 6 of the link will enter the draw-head *a'*, strike the shoulder 9 of the dog *b'* therein, and turn it into engagement with the said link, and by the said movement allow the block *e* to fall and lock the said dog 25 and link together, and thereby retain the cars shackled as long as desired.

When desired to unshackle the cars the operator raises one of the levers *n*, as shown at the right of Fig. 2, thereby causing the lifting-toe *i* to raise the block *e* until it comes 30 into line with the recess 8 of the dog *b* or *b'*, leaving the said dog free to turn on its pivot, so that as soon as any strain is brought on the link *c* its holding-point 4 acts on the point *B* 35 of the dog and turns it aside, the link then passing out from the draw-head, and leaving it, as shown at the right hand, Fig. 2, ready to again receive a link when desired to again shackle together the cars.

40 To provide for the use of my improved coupling on one car in co-operation with the ordinary link-pin coupling on another car, the thin end 6 of the link *c* may be provided with an eye, 10, as shown in Fig. 3, to receive the 45 pin.

I am aware that couplings have been constructed with a connecting-bar having at each end a flat circular terminal, which, on entering the draw-head, forces back a pivoted tumbler, 50 and is held between said tumbler and a roller, said tumbler being held in position to retain the connecting-bar by means of a spring-dog, which takes into a notch on the rear of the tumbler. This arrangement, however, is ob- 55 jective, for the reason that upon withdrawal, strain being exerted upon the connecting-bar, it will draw with it the forward part of the tumbler, and consequently raise the

rear portion thereof, and as this rear portion rises the spring-dog will be pushed out of contact with its engaging notch, and thus cause the unauthorized release of the coupling.

In my construction no such danger as an automatic and unauthorized release of the coupling-bar is possible, because the V-projection 3 enters and is rigidly held within a corresponding-shaped notch, 4, immediately on which entry the pivoted block *e* drops down between the holding end 3 of the dog and the side of the draw-head, from which position it 70 cannot be removed except by raising the lever *n*, which operates to lift the toe *i* and raise the block *e* out of locking contact.

I claim—

1. In a car-coupling, the draw-head and a 75 dog, *b*, pivoted therein, and provided with a V-shaped holding-point, 3, and squared shoulder 9, combined with a connecting-link, *c*, having a notch, 4, to engage the holding-point of the dog, and an end to abut against the squared 80 shoulder of the dog, to rotate said dog on its pivot and throw its holding-point into the notch, substantially as shown.

2. In a car-coupling, the draw-head, a pivoted dog therein having a holding-point, 3, and shoulder 9, and a connecting-link having a notch to receive the point 3, combined with a pivoted locking-block, *e*, adapted to fall in between the draw-head face and the side of the dog, to lock said dog with the link, substantially as 85 described.

3. In a car-coupling, the draw-head and holding-dog pivoted therein, combined with the locking-block *e*, to retain the said dog in engagement with the link, and a lifting-toe, *i*, 95 and means to operate it to raise the said locking-block, and thereby release the dog and link, substantially as described.

4. In a car-coupling, the draw-heads and holding-dogs therein, combined with a link to 100 be engaged by the said dogs, it being at one end of substantially the size of the opening in the draw-head, to fit snugly and be held squarely therein, and at its other end of considerably less thickness vertically, to enable it to 105 enter a draw-head at a different height from the rails from the one in which the link is snugly fitted, substantially as and for the purpose described.

In testimony whereof I have signed my 110 name to this specification in the presence of two subscribing witnesses.

MICHAEL DOWNEY.
